[57] **CLAIM**

The ornamental design for a blocking hat rack, as shown and described.

DESCRIPTION

FIG. 1 is a left side elevational view of a blocking hat rack showing my new design, the broken-line disclosure of a hat being for illustrative purposes only and forming no part of the claimed design;

FIG. 2 is a bottom, front, and left side perspective view thereof;

FIG. 3 is a front elevational view thereof;

FIG. 4 is a left side elevational view thereof, the right side being a mirror image of that shown; and,

FIG. 5 is a top, front, and right side perspective view thereof.

FIG. 3

FIG. 4

FIG. 5
